INSECT CATCHER

Maurice G. Laberge, 9209 Airlie Blvd.,
Ville Lasalle, Quebec, Canada

Filed Mar. 15, 1963, Ser. No. 73,991

Term of patent 14 years

(Cl. D31—3)

FIG. 3

FIG. 4

FIG. 1

FIG. 2

FIG. 5

FIG. 6

FIG. 1 is a perspective view of an insect catcher, showing my new design in open position;

FIG. 2 is an elevation of one side thereof;

FIG. 3 is an elevation of the opposite side thereof;

FIG. 4 is an elevation of the rear end thereof;

FIG. 5 is an elevation of the front end thereof; and

FIG. 6 is a front end elevation similar to FIG. 5, showing the insect catcher in closed position.

I claim:

The ornamental design for an insect catcher, substantially as shown.
